ELECTRIC DRILL UNIT

Alec Bradley Kirkbride, London, England, assignor to
B. Elliott & Company Limited, London, England, a
British company

Application August 5, 1957, Serial No. 47,240

Term of patent 14 years

(Cl. D54—14)

Fig. 1 is a front perspective view of an electric drill unit showing my new design.

Fig. 2 is a front perspective view from below and the opposite side.

The rear of the body portion of the drill unit is substantially plain except for a circular opening near the top for an electric cord; the ornamental beading continues around the rear of the handle.

I claim:

The ornamental design for an electric drill unit, as shown and described.
